LEG UNIT FOR A WORKTABLE

John K. Williamson, Toronto, Ontario, Canada, assignor
to National Machine Products Limited, Downsview,
Ontario, Canada

Filed Mar. 15, 1971, Ser. No. 124,623

Term of patent 14 years

Int. Cl. D6—06
U.S. Cl. D6—194

FIG. 1

FIG. 2

FIG. 3

FIG. 1 is a view from above of a leg-unit for a worktable, the view showing my new design;

FIG. 2 is a view from below of the leg unit illustrated in FIG. 1, the leg unit being shown as viewed in the direction opposite to the direction in which the leg unit is viewed in FIG. 1; and

FIG. 3 is a side view of the leg unit illustrated in FIGS. 1 and 2.

I claim:

The ornamental design for a leg unit for a worktable, as shown.
